UNITED STATES PATENT OFFICE.

FRANK M. ROBBINS, OF MARION, INDIANA, ASSIGNOR TO POSITIVE RAIL ANCHOR COMPANY, OF MARION, INDIANA, A CORPORATION.

ANTICREEPING DEVICE FOR RAILWAY-RAILS.

1,264,209.

Specification of Letters Patent. Patented Apr. 30, 1918.

Application filed March 26, 1917. Serial No. 157,506.

To all whom it may concern:

Be it known that I, FRANK M. ROBBINS, a citizen of the United States, residing at Marion, in the county of Grant and State of Indiana, have invented certain new and useful Improvements in Anticreeping Devices for Railway-Rails, of which I do declare the following to be a full, clear, and exact description, reference being had to the accompanying drawings, forming part of this specification.

The present invention has for its object to provide an improved construction of rail anchor or "anti-creeping" device, whereby the "creeping" or longitudinal movement of railway rails will be prevented. The invention consists in the novel features of construction hereinafter described, illustrated in the accompanying drawings and particularly pointed out in the claims at the end of the specification.

Figure 1 is a plan view of a railway rail showing one form of my invention applied thereto, a portion of the rail being broken away. Fig. 2 is a view in vertical section on line 2—2 of Fig. 1. Fig. 3 is a view in vertical section on line 3—3 of Fig. 1. Fig. 4 is a view similar to Fig. 1 but showing a somewhat modified form of the invention. Fig. 5 is a view in vertical section on line 5—5 of Fig. 4. Fig. 6 is a plan view showing a further modification of my invention. Fig. 7 is a view in vertical section of line 7—7 of Fig. 6. Fig. 8 is a view in vertical section on line 8—8 of Fig. 6.

In Figs. 1 to 5 of the drawings, my invention is shown as applied to tie plates, and in Figs. 6 to 8 of the drawings, the invention is shown as applied to one familiar type of rail anchor commonly known as the "Positive" rail anchor. It will be understood, however, that the invention is susceptible of more general application and that the details of the invention hereinafter described may be varied without departing from the scope of the invention.

In Figs. 1 to 5 of the drawings, A designates the body of a tie plate, which with my invention applied thereto, also constitutes an anti-creeping device, this tie plate being

shown as formed with lugs or flanges a and a' at opposite sides, adapted to engage respectively the base flanges b and b' of the railway rail B. As shown, the rail gripping flanges a and a' are in offset relation and the tie plate is provided with openings a^2 to receive spikes whereby it may be fastened to the cross tie of the track in usual manner.

The upper surface of the plate A is provided with an inclined seat to receive a roller adapted to exert an upward pressure upon the rail in order to prevent the longitudinal movement or creeping of the rail. In the form of the invention illustrated in Figs. 1 to 3 of the drawings, the seat a^4 is shown as inclined upwardly in opposite directions from the center and is formed at the bottom with a depression or pocket extending transversely of the face A, and upon the seat a^4 rests a roller C that extends transversely of the plate A and is of such diameter as to project slightly above the face of the plate so as to engage the under side of the base of the rail B. The roller C should be a hard steel roller and the seat should be formed of harder metal than the body of the plate A. Preferably, the seat for the roller C may consist of an inserted strip of hardened steel, as shown in Fig. 3, or the inclined bottom of the depression or pocket in which the roller C rests might be chilled in the casting operation so as to give it a greater hardness than the body of the plate.

When the plate A has been placed in position upon the rail, as indicated in the drawing, with its flanges a and a' engaging respectively the base flanges b and b' of the rail, the bottom face of the rail base will rest upon the roller C. Any tendency of the rail to creep will cause the roller C to travel up the inclined seat at the top of the plate A and will cause the roller to exert an upward thrust upon the rail, firmly binding it between the roller and the flanges a and a' by which such upward thrust is resisted. Inasmuch as the seat a^4 is oppositely inclined, as shown in Fig. 3, the roller C will serve to wedge against the base of the rail, regardless of the direction in which the rail may tend to creep.

In the modified form of the invention illustrated in Figs. 4 and 5 of the drawings, the plate A has rail gripping flanges a and a' and spike holes a^2 , as in the construction hereinbefore described, but in this form of the invention, the plate A is formed at one end with an abutment D adapted to bear against one side of a cross tie E of the track; and the upper portion of this abutment D is provided with a seat or seats a^6 at the base of a pocket or pockets a^7 to receive the roller or rollers C. It is obvious that instead of a single roller, there may be a plurality of rollers and for this reason I have shown two individual rollers in Fig. 4 of the drawings, these rollers resting upon seats a^6 within individual pockets. The abutment D, by its engagement with the side of the cross tie E, will prevent any longitudinal movement of the cross tie in the direction of the arrow, Fig. 5. The seat a^6 shown in Figs. 4 and 5 is inclined in one direction only and the plate is therefore best adapted for use on double track roads where the travel, on each track is in one direction. By reference to Fig. 5, it will be seen that any tendency of the rail B to creep in the direction of the arrow there shown, will cause the roller C to move slightly up the inclined seat a^6 , thereby causing the roller to exert an upward thrust upon the base of the rail B, this thrust being resisted by the flanges a and a' , as in the construction hereinbefore described and the rail will thus be held against creeping in the direction of the arrow, Fig. 5.

In Figs. 6 to 8 of the drawings, my invention is shown as applied to a familiar type of rail anchor known upon the market as the "Positive" rail anchor, this anchor comprising a body member A² adapted to extend beneath the base of the rail and being provided at its ends with rail gripping flanges a^8 and a^9 . At one of its ends, the body member A² is formed with a depending abutment D' cast integral therewith and adapted to bear against one side of the cross tie E. In this form of my invention, the upper face of the body member is provided with a seat a^{10} formed at the bottom of a pocket or depression to receive the roller C, this seat a^{10} being oppositely inclined from the center, as in the construction illustrated in Fig. 3 of the drawings. The seat a^{10} may be rendered harder than the body A² of the anchor by chilling the metal of the seat, or an inserted seat, such as indicated in Fig. 3, might be used. Preferably, the seat a^{10} is located adjacent the end of the anchor farthest from the abutment D', as clearly shown in the drawings, and this part of the anchor may be thickened, as indicated in Fig. 8, to avoid weakening the body member A² by the formation therein of the pocket that

receives the roller C. With the form of anchor illustrated in Figs. 6 to 8, the tendency of the rail B to creep in the direction of the arrow shown in Fig. 6 will cause the flange a^8 to move slightly toward the tie E, such movement increasing the grip or "shackle" action of the anchor on the rail flanges b and b' . As the body member A² of the anchor is thus shifted slightly in the initial movement of the rail B, the roller C will move slightly along the inclined seat a^{10} and will exert an upward thrust upon the rail B, wedging the base flanges of the rail between the roller and the flanges a^8 and a^9 of the body member A². In case of any backward movement of the body member A², that is to say, a movement in the direction opposite that shown by the arrow in Fig. 6, the roller C would move slightly along that portion of the inclined surface a^{10} nearest the tie E and would wedge the anchor firmly to the rail base, so that all danger of the working loose of the anchor would be avoided.

Having thus described my invention, what I claim as new and desire to secure by Letters Patent is:—

1. An anti-creeping device for railway rails, comprising a member adapted to extend beneath the base of the rail and provided with an upwardly facing, double inclined seat, and a roller located on said seat and adapted to exert upward pressure on the rail.
2. An anti-creeping device for railway rails, comprising a member adapted to extend beneath the base of the rail and provided with an upwardly facing seat of harder material than the body of said member, and a roller located on said seat and adapted to exert upward pressure on the rail.
3. An anti-creeping device for railway rails, comprising a body member adapted to extend beneath the base of the rail and having at its end flanges to engage the base flanges of the rail and having beneath one of said flanges an offset abutment at one end for extending toward one of the cross ties of the track and adapted to produce a shackle action of the device to resist the creeping movement of the rail, said body member being provided upon its upper side adjacent the rail engaging flange farthest from said abutment with a movable part located at one side of the transverse center of the body member to exert an upward thrust on the under side of the rail flange farthest from said abutment.
4. An anti-creeping device for railway rails, comprising a body member adapted to extend beneath the base of the rail and having at its end flanges to engage the base flanges of the rail and having at one end

and at one side of its transverse center an offset abutment extending toward one of the cross ties of the track and adapted to produce a shackle action of the device to 5 resist the creeping movement of the rail, said body member being provided at the opposite side of its transverse center and adjacent the rail engaging flange farthest from said abutment with an upwardly fac- 10 ing inclined seat and a roller located on said seat and adapted to exert an upward pres-
sure on the rail base.

FRANK M. ROBBINS.
